ABSTRACT OF THE DISCLOSURE

A cushion assembly comprising at least one spring, a clip supporting the end of the spring and a frame for supporting the clip. The clip has a substantially U-shaped metallic body including a pair of generally opposed first and second flanges joined by a central web portion. The first flange has a pair of holes therethrough and a fifth hole. Either a staple is disposed in each of the two pairs of holes or a screw, nail or the like is disposed in the fifth hole, or both.

This invention relates to a clip utilized in a cushion assembly for retaining the ends of sinuous spring strips to the front and rear rails of the frame of the assembly.

It is an object and feature of this invention to provide a novel clip for securing the ends of a sinuous spring to a frame in a cushion assembly.

FIGURE 1 is a fragmentary perspective view of a cushion assembly including the clip of the instant invention secured by a first means to the frame of the assembly; and

FIGURE 2 is a fragmentary perspective view of a cushion assembly including the clip of the instant invention secured by a second means to the frame of the assembly.

Referring to the drawings, wherein like numerals indicate like or corresponding parts in both views, a cushion assembly is generally shown at 10 and includes a sinuous spring strip 12, a clip for supporting the end of the spring 12 and generally indicated at 14, and a frame 16 for supporting the clip 14.

The clip 14 has a substantially U-shaped metallic body including a pair of generally opposed first and second flanges 18 and 20 which are joined by a central web portion 22.

A material 24 is disposed on the inner face of the clip body and preferably comprises a paper layer impregnated or coated with a low friction material, such as polyethylene, Teflon or the like.

The first flange 18 has two pair of holes 26 and 28 therethrough. In addition, the first flange also has a fifth hole 30 therethrough. The first flange 18 is longer than the second flange 20, and the first flange is disposed on the frame 16. The frame 16 is preferably made of wood. The holes of the two pair of holes 26 and 28 are of equal size and are smaller than the fifth hole 30. The holes of the two pair of holes 26 and 28 are equally spaced from one another and the fifth hole 30 is spaced an equal distance from each of the holes of the two pair 26 and 28.

In the embodiment of FIGURE 1, a means comprising the screw 32 is disposed through the fifth hole 30 and into the wooden frame to secure the clip 14 on the frame 16. Alternatively, a nail may be utilized in place of the screw 32. In the embodiment illustrated in FIGURE 2, a staple 34 is disposed in each pair of the two pair of

2

holes 26 and 28. In some environments, a screw 32 or a nail is inserted through the hole 30 to secure the clip 14 to the wooden frame 16; however, in other environments it is preferable to utilize the staples 34 to secure the clip to the wooden frame 16. In addition, both means for securing the clip 14 to the wooden frame 16 may be utilized.

The invention has been described in an illustrative manner and it is to be understood that the terminology which has been used is intended to be in the nature of words of description rather than of limitation.

Obviously, many modifications and variations of the present invention are possible in light of the above teachings. It is, therefore, to be understood that within the scope of the appended claims, the invention may be practiced otherwise than as specifically described.

The embodiments of the invention in which an exclusive property or privilege is claimed are defined as follows:

- 20 1. A cushion assembly comprising at least one spring, a clip supporting the end of said spring, and a frame for supporting said clip, said clip having a substantially U-shaped metallic body including a pair of generally opposed first and second flanges joined by a central web portion, said first flange having two pair of holes therethrough, said first flange having a fifth hole therethrough, and means disposed in one of said fifth hole and said two pair of holes for securing said clip to said frame.
- 25 2. An assembly as set forth in claim 1 wherein said first flange is longer than said second flange, said first flange being disposed on said frame, said two pair of holes being of equal size and smaller than said fifth hole.
- 30 3. An assembly as set forth in claim 2 wherein said holes of said two pair of holes are equally spaced from one another and said fifth hole is spaced an equal distance from each of said holes of said two pair.
- 35 4. An assembly as set forth in claim 3 wherein said frame is made of wood and said means extends through said fifth hole and into said wooden frame to secure said clip on said frame.

- 40 5. An assembly as set forth in claim 3 wherein said frame is made of wood and said means extends through said holes of said two pair and into said wooden frame to secure said clip on said frame.
- 45 6. An assembly as set forth in claim 5 wherein said means comprises a staple disposed in each pair of said two pair of holes.

- 50 7. A clip for supporting the end of a spring in a furniture assembly and comprising a substantially U-shaped metallic body including generally opposed first and second flanges joined by a central web portion, said first flange having two pair of holes therethrough and adapted to receive staples for securing said clip to a support structure, said first flange having a fifth hole therethrough and adapted to receive means for securing said clip to a support structure.
- 55 8. A clip as set forth in claim 7 wherein said first flange is longer than said second flange and said holes of said two pair are of equal size and smaller than said fifth hole.

- 60 9. A clip as set forth in claim 8 wherein said holes of said two pair are equally spaced from one another and said fifth hole is spaced an equal distance from each of said holes of said two pair.
